UNITED STATES PATENT OFFICE.

OSCAR LEONARD BAXTER, OF HOMEWOOD, ILLINOIS, ASSIGNOR TO SOLAR-STUBGES MANUFACTURING COMPANY, OF CHICAGO, ILLINOIS, A CORPORATION OF ILLINOIS.

COUNTERWEIGHTED COVER FOR WASTE RECEPTACLES.

Application filed June 23, 1923. Serial No. 647,390.

To all whom it may concern:

Be it known that I, OSCAR LEONARD BAXTER, a citizen of the United States, and a resident of Homewood, in the county of Cook and State of Illinois, have invented certain new and useful Improvements in a Counterweighted Cover for Waste Receptacles; and I do hereby declare that the following is a full, clear, and exact description of the same, reference being had to the accompanying drawings, and to the numerals of reference marked thereon, which form a part of this specification.

This invention relates to a waste receptacle of that type designed to receive waste paper and other refuse and which is usually placed upon a street corner or in buildings and factories, into which employees may deposit waste matters.

It is among the objects of this invention to produce such a receptacle which is always closed, having automatically operated doors or panels through which waste matters may be deposited within the can.

This invention comprises the novel mechanism and combinations hereinafter described and more particularly pointed out and defined in the appended claim.

In the accompanying drawings which illustrate a preferred embodiment of this invention and in which similar reference numerals refer to similar features in the different views,

Fig. 1 is a top plan view of the waste receptacle;

Fig. 2 is a vertical section upon the line 2—2 of Fig. 1.

Fig. 3 is an enlarged section taken upon the line 3—3 of Fig. 2 showing parts in elevation, and

Fig. 4 is a section upon the line 4—4 of Fig. 3.

Referring to the drawings, the receptacle is illustrated as consisting of sheet metal or the like having a body portion 1 of polygonal cross section, but the same may be of any desired shape. The method of making such a receptacle is well known and needs no detail description. The upper end 50 of the receptacle is closed by a removable cover or top 2 having sloping sides 3 and

sloping ends 4 producing what may be termed a peaked cover. The lower margins of the cover are folded upon themselves with the ends of the folded portions stamped 55 with arcuate ledges 5 that are adapted to take over the upper edges of the receptacle and form supports for the cover.

Openings or apertures for doors are cut in the sides of the cover 2 and doors 6 are 60 hinged to the cover at their upper ends in these openings and open inwardly. In the present instance, a pair of angle irons 7 are secured to the under side of each door and are bent inwardly at substantially right 65 angles at their upper ends to form supports for the counter weights 8 which are secured thereto.

A pair of angle irons 9 are secured upon the interior of each side of the cover; the 70 secured flanges of these angles have their lower end terminating at the upper edges of the openings, while the upstanding flanges project downwardly beyond the openings so as to overlap the upstanding 75 flanges of the angle irons 7, and pivots or rivets 10 extend through these overlapped portions to form the pivotal or hinge connections. The lower ends of the doors 6 are slightly bent downwardly and are adapted 80 to normally rest against the lower margins of the openings which are crimped over as indicated at 11 to form abutments, against which the lower margins of the doors are adapted to strike as they are automatically 85 closed by the counter weights 8.

In referring to Fig. 2, which shows the right hand door open and the left hand door closed, it will be noted that gravity is always acting upon the counter weights so as 90 to close the doors. When it is desired to deposit something in the receptacle, it is only necessary to push it against one of the doors which will automatically swing inwardly to allow the matter to drop in the 95 receptacle. As soon as the pressure against the door is released, it will automatically swing to its closed position through the force of gravity acting on the counter weight.

I am aware that numerous details of construction may be varied through a wide range without departing from the principles 100

of this invention, and I therefore do not to said door and having angled counter-purpose limiting the patent granted otherwise than necessitated by the prior art.

I claim as my invention:

- 5. In a waste receptacle, a body portion, a cover therefor having a sloping surface and having an aperture therein, a door for closing said aperture, angle irons secured

to said door and having angled counter-weighted ends, angle irons secured to said cover and having parts overlapping the angle irons on said door, and pivots extending through said overlapping portions.

In testimony whereof I have hereunto subscribed my name.

OSCAR LEONARD BAXTER.
